Primary Examiner — Ian Simmons*Assistant Examiner* — Ieisha N Price(74) *Attorney, Agent, or Firm* — Sheridan Ross PC**(57) CLAIM**

The ornamental design for a vehicle rack support tower, as shown and described.

DESCRIPTION

FIG. 1 is a front perspective view of a vehicle rack support tower;

FIG. 2 is a rear perspective view of a vehicle rack support tower;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The broken lines in the drawings illustrate portions of the vehicle rack support tower and form no part of the claimed design.
